UNITED STATES PATENT OFFICE.

LUTHER D. SHEPARD, OF BOSTON, MASSACHUSETTS.

HOLDER FOR ABRASIVE DISKS.

SPECIFICATION forming part of Letters Patent No. 282,385, dated July 31, 1883.

Application filed May 19, 1883. (No model.)

To all whom it may concern:

Be it known that I, LUTHER D. SHEPARD, of Boston, county of Suffolk, State of Massachusetts, have invented an Improvement in Holders for Abrasive Disks, of which the following description, in connection with the accompanying drawings, is a specification, like letters on the drawings representing like parts.

My invention relates to means for packing and preserving in good condition abrasive disks, such as are employed by dentists for cutting and polishing the teeth or metal fillings therein. These disks are generally made of paper or other somewhat flexible material, to one side of which powdered glass or emery or other abrasive substances are applied by glue or cement in the usual manner, and the said disks are in many cases also treated with shellac or other similar material to give the disks the requisite stiffness. Disks treated in this manner, if left to themselves, will become warped or bent, and consequently will not run true when rotated in the lathe or engine. Such warping is obviated by the holder forming the subject of the present invention, by means of which the disks are retained perfectly flat and occupy the least possible space, they forming a package that may be conveniently handled or packed for shipment.

The package or holder consists, essentially, of two rigid plates or followers, preferably of the same shape and a trifle larger than the disks which are to be packed between them, combined with springs tending to draw the said plates toward one another to compress the disks packed between them, and thus retain them perfectly flat, and a central spindle to keep the said disks in coincidence with one another. The plates are provided with ears or lugs to receive the springs, which extend along the sides of the cylindrical pile of disks, and the spindle or wire is run through the central openings of the disks by which they are to be subsequently applied to the mandrel of the engine.

Figure 1 is a plan view, and Fig. 2 a front elevation, of a series of disks packed in a holder in accordance with this invention.

The holder consists of two rigid plates, *a b*, preferably a trifle larger in diameter than the

disks, *c*, to be packed and held between them. The said plates *a b* are provided with ears or hooks *d*, to receive the ends of springs *e*, (shown in this instance as rubber bands,) by which the said plates are drawn toward one another and compress the disks *c* between them, preventing the said disks from warping, and keeping them perfectly flat until they are removed and put in use.

The disks are provided with the usual central opening for attaching them to the mandrel of the lathe or engine by which they are to be operated, and when the said disks are placed in coincidence with one another in a cylindrical pile, the said openings form a central tubular passage through the said pile; and in order to keep the disks in coincidence with one another and prevent any of them from pushing out from between the holding-plates *a b* the package of disks is provided with a central spindle or wire, *f*, passed through the central openings of the disks and through corresponding openings, 2, in the plates *a b*. The said wire *f* is bent at one end, as shown, to engage the adjacent plate *a*, and the other end, which projects through the central passage of the package, may be bent down upon the other plate to retain the wire in place until the disks are to be used, when it will be bent back into line with the axis of the package to enable the disks to be removed. When in this condition, as shown in the drawings, the wire will be retained in place or prevented from becoming disengaged from the package by its friction therein, the said wire being substantially as large in diameter as the holes in the disks.

The disks, when held as herein described, form a convenient package for shipment, or to be laid away or stored until the disks are desired for use, when they may be removed from the package and put in a holding apparatus—such as described in another application filed by me May 10, 1883; or, if desired, the disks may be removed one by one from the package and used, the holding-plates operating to keep the remainder flat until all are used up.

I claim—

The combination, with a pile of flexible

abrasive disks, of the rigid plates *a b*, engaging the ends of the said pile, the springs connecting the said plates and pressing them against the ends of the pile, and the spindle 5 *f* passing through the central opening in the said disks and plates, substantially as described.

In testimony whereof I have signed my name to this specification in the presence of two subscribing witnesses.

LUTHER D. SHEPARD.

Witnesses:

Jos. P. LIVERMORE,
W. H. SIGSTON.
